ATTORNEYS,

UNITED STATES PATENT OFFICE.

LEBRECHT FRITZSCHE, OF NEWARK, NEW JERSEY.

DESIGN FOR A MATCH-BOX.

SPECIFICATION forming part of Design No. 31,400, dated August 15, 1899.

Application filed July 20, 1899. Serial No. 724,564. Term of patent 3½ years.

To all whom it may concern:

Be it known that I, LEBRECHT FRITZSCHE, a citizen of the United States, residing at Newark, in the county of Essex and State of New Jersey, have invented and produced a new and original Design for Match-Boxes; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

5 In the accompanying drawings, Figure 1 is a side view of a match-box of my new design; and Fig. 2 is a section of the same on line *x*, Fig. 1.

As shown in the drawings, the leading or material feature of my new design consists in a match-box having its sides bordered by a series of scrolls and having a double line of scroll-like ornamentalations extending across the side of the box at the line of meeting of 5 the box-body and its cover.

In said drawings, *a* indicates the body portion of the match-box, and *b* the cover, the bottom corners of said body being beveled, as at *c*, at the front and rear edges of the box. 5 Starting at the bottom of the box, each side of the box-body is ornamented by a centrally-disposed trifoliate figure *d*, and on each side of said trifoliate figure is a foliated scroll *e*, adjacent to the beveled corner of the box.

The front and rear margins of the sides of the 35 box-body are each bordered by a central inwardly-facing scroll *f*, while above and below said central scroll are small outwardly-facing scrolls *g*.

At the upper corners of the sides of the 40 cover *b* of the box are displayed outwardly-rounded scrolls *h*, and between these corner-scrolls at the top of the box are small outwardly-curved scrolls *i*, while below the corner-scrolls at the front and rear edges of the 45 cover are outwardly-facing scrolls *j*.

Adjacent to the line of meeting of the box body and cover both said body and cover are ornamented by opposite centrally-disposed trifoliate ornamentalations *k*, and at both 50 sides of said trifoliate ornamentalations *k* are scrolls *l*, arranged close to the line of meeting of the box and cover and having the convex side toward said line.

The middle portion of each side of both box 55 body and cover is thus a plain field *m*, bordered by a series of scrolls.

What I claim as new is—

The design for a match-box as herein shown and described. 60

In testimony that I claim the foregoing I have hereunto set my hand this 9th day of June, 1899.

LEBRECHT FRITZSCHE.
